INVERTIBLE CONTAINER

Wayne W. Bissell, New Castle, Pa.

Application March 8, 1934, Serial No. 714,718

7 Claims. (Cl. 215—12)

My invention relates to containers of the type in which an inner vessel is provided with a decorative covering, and it consists in the combinations, constructions and arrangements herein described 5 and claimed.

An object of my invention is to provide an improvement over that form of the device shown in my prior application No. 684,432, filed Aug. 9, 1933.

10 In said prior application I disclosed a device comprising an inner receptacle having a decorative covering made up in segments, the inner receptacle and the decorative covering being held rigidly in position.

15 A main feature of the present invention consists in the provision of a decorative covering made up of segments which can be inverted so as to change the contour and appearance of the container, and in which the decorative covering 20 is held firmly in either position.

A further object is to provide a container having a decorative covering of the type described in which the contour or shape of the container may be varied without necessitating the fabrication of additional segments, thereby providing 25 an economical means for making containers of different shapes.

Other objects and advantages will appear in the following specification and the novel features 30 of the invention will be particularly pointed out in the appended claims.

My invention is illustrated in the accompanying drawing forming part of this application, in which:

35 Figure 1 is a central sectional view showing one embodiment of my invention.

Figure 2 is a view showing the decorative covering of Fig. 1 inverted.

Figure 3 is a sectional view showing a modified form.

Figure 4 is a sectional view of an inverted form of the covering shown in Fig. 3.

Figure 5 is a sectional view of another modified form, and,

45 Figure 6 is a sectional view showing the covering of Fig. 5 inverted.

Referring now particularly to Figs. 1 and 2, I have shown therein an inner receptacle, which is provided with a bottom flange or abutment member 2, and which is threaded at its top, as shown at 3. A lower section or segment 4, of a decorative covering is provided and as will be observed, this segment has an inwardly extending flange 5 which engages the abutment flange 2. The upper section 6 has an articulated joint 7 by means

of which it is connected to the lower section 4. An inwardly extending flange 8 is provided for the upper section 6.

A ring-shaped section 9 is threaded internally to engage the threaded portion 3 of the container. The outer face of this ring-shaped portion 9 is beveled so as to receive a cover 10 which is held in place frictionally.

In assembling the device the lower portion is slipped over the container until the flange 5 rests on the abutment flange 2. The upper segment is placed in position, the ring 9 is screwed down until it engages the upper portion of the flange 8, and the cover is then put on. Thus it will be seen that the decorative covering sections or segments are clamped between the ring 9 and the abutment flange 2.

The sections 4 and 6 are of different contour but it will be observed that the flanges 5 and 8 project the same distance toward the receptacle. 75 In other words, the opening between the opposite edges of the flange 8 is the same as that of the flange 5. As a consequence these sections may be reversed in position as shown in Fig. 2, by unscrewing the ring 9, lifting the decorative covering off from the receptacle, inverting it, and then replacing the ring so that the shoulder 11 of the ring now engages the flange 5 to clamp the sections of the decorative covering between the shoulder 11 and the abutment flange 2 of the 80 receptacle.

In Fig. 3, I have shown an inner receptacle 12 which is provided with an abutment plate 13, held by a screw 14 threaded into a boss 15 in the bottom of the receptacle. A lower segment or section 16 has a flange 17 which engages the abutment plate 13, and an upper section 18 having a flange 19 which is engaged by a ring 20 threaded to the container and capped by a cover 21. In Fig. 4 the decorative covering is shown in reversed position from that indicated in Fig. 3 and as is the case with the form shown in Fig. 2, it differs in contour from that form shown in Fig. 3, although made of the same segments.

In Fig. 5 the inner container 21 is provided with an abutment plate 22 which is held by means of a screw 23, the upper end of the screw bearing a nut 24. The lower section 25 of the decorative covering has a flange 26 which engages the abutment 22. An upper section 27 has a flange 28 provided with a recess to receive the portion 29 of the top, and this recess corresponds to one in the lower section which receives a portion 30 of the bottom.

A cover portion 31 is provided having a flange 110

32 arranged to enter an annular recess in the member 27. The nut 24 has a slot 23 which is arranged to register with a slot 34 when the cover 31 is turned to a position at right angles to that 5 shown in Fig. 5. This construction of the nut and slot means for permitting the dispensing of material within the receptacle was disclosed in my prior patent application No. 691,714, filed Sept. 30, 1933, and forms no particular part of the 10 present invention except so far as the parts cooperate with the decorative covering to permit the covering to be inverted so as to form a container of different contour from the same parts, such as that shown in Fig. 6. In Fig. 6 it will 15 be observed that the lower section 25 now becomes the upper section and the upper section 27 now the lower. The flange 32 of the cover 31 now rides in the annular slot 35 of the member 25.

It will be observed that in all of these forms the 20 inner container has an abutment against which the lower segment or section of the decorative covering rests, and that the sections have inwardly projecting portions which are symmetrical with the central axis of the container, and which 25 cooperate with the other parts to hold the inner receptacle firmly and to form a container in which the decorative covering is rigidly held in either position. The particular use to which 30 these invertible decorative coverings may be put is in the cosmetic trade.

Duplicate containers can be decorated with 35 duplicate coverings even as to color, and yet by inverting the cover members on one of the pair a difference in shape is created to make visual differentiation of the two preparations a matter of a glance.

A further great advantage in each structure is the fact that one set of molds and tools creates 40 two designs, an important item of manufacturing economy.

I claim:

1. A container comprising an inner receptacle, a decorative covering therefor comprising a pair 45 of sections of different contour, said covering being invertible, and means for rigidly securing covering in either position to the container.

2. A container comprising an inner receptacle having an abutment member, a decorative covering therefor including a pair of sections of 50 different contour, said decorative covering being invertible to engage the abutment in either position, and means for clamping the decorative covering to said container in either position.

3. A container comprising an inner receptacle 55 having an abutment member, a decorative covering therefor including a pair of sections of different contour having interlocking edges, each section being provided on its opposite edge with an inwardly extending annular flange of the same 60 internal diameter, either of said flanges being adapted to engage said abutment, and means for engaging the other flange and cooperating with the abutment to clamp the sections together.

4. A container comprising an inner receptacle threaded at its upper end and having an abutment member, a decorative covering therefor including a pair of sections of different contour having interlocking edges, each section being provided on its opposite edge with an inwardly extending annular flange of the same internal diameter, either of said flanges being adapted to engage said abutment, a threaded ring arranged to engage the threaded portion of said inner receptacle and adapted to bear on the flanges of one of said sections for clamping said sections together. 80

5. A container comprising an inner receptacle threaded at its upper end and having an abutment member, a decorative covering therefor including a pair of sections of different contour having interlocking edges, each section being provided on its opposite edge with an inwardly extending annular flange of the same internal diameter, either of said flanges being adapted to engage said abutment, a threaded ring arranged to engage the threaded portion of said inner receptacle and adapted to bear on the flanges of one of said sections for clamping said sections together. 90

6. A container comprising an inner receptacle having an upper threaded portion, an abutment plate secured to the bottom of said receptacle, a decorative covering for said inner container comprising a pair of sections of different contour having interlocking edges, each section being provided on its opposite edge with an inwardly extending annular flange of the same internal diameter, either of said flanges being adapted to engage said abutment plate, an internally threaded ring arranged to engage the threads of the inner receptacle and to bear on the flange of one 100 of said sections for clamping the sections together. 105

7. A container comprising an inner receptacle having an abutment plate disposed underneath said inner receptacle, a centrally disposed screw 120 for holding the abutment plate, a decorative covering for said inner receptacle including a pair of sections of different contour having interlocking edges, each section being provided on its opposite edge with an inwardly extending annular flange 125 of the same internal diameter, either of said flanges being adapted to engage said abutment plate and the container, a cover portion arranged to engage the annular flange of the other section, and a nut for holding the cover plate in sliding 130 relation with the flange, said nut being threaded on said screw and being provided with a slot, and the cover plate having a slot arranged to register with the slot in the nut when the cover plate is rotated to a predetermined position. 135
